UNITED STATES PATENT OFFICE.

ARTHUR JAMES BAZELEY, OF CLEVELAND, OHIO, ASSIGNOR TO THE NATIONAL MALLEABLE CASTINGS COMPANY, OF CLEVELAND, OHIO, A CORPORATION OF OHIO:

CAR-COUPING.

No. 844,491.

Specification of Letters Patent.

Patented Feb. 19, 1907.

Application filed November 11, 1904. Serial No. 282,310.

To all whom it may concern:

Be it known that I, ARTHUR JAMES BAZELEY, of Cleveland, Cuyahoga county, Ohio, have invented a new and useful Car-Coupling, 5 of which the following is a full, clear, and exact description, reference being had to the accompanying drawings, forming part of this specification, in which—

Figure 1 shows two interlocked couplers embodying my invention, one being shown in plan and the other in horizontal section. Fig. 2 is a side elevation, one of the couplers being partly broken away. Fig. 3 is a front elevation of one of the couplers, partly in vertical 15 section. Fig. 4 is a horizontal section on the line IV IV of Fig. 3. Fig. 5 is a vertical section on the line V V of Fig. 3, but showing the coupler unlocked. Fig. 6 is a similar view showing the parts in lock-set position. Fig. 20 7 is a front elevation of the locking and opening piece. Fig. 8 is a horizontal section on the plane of the operating-shaft, showing the coupler in unlocked and open position. Fig. 9 is a vertical section on the line IX IX of Fig. 25 8. Fig. 10 is a horizontal section showing the roof of the coupler-head viewed from below. Fig. 11 is a vertical section of the coupler-head viewed from the rear, showing a modified construction of lock-tripping device, 30 35 the lock being shown in lock-set position by full lines and in locked position by dotted lines. Fig. 12 is a longitudinal vertical section on the line XII XII of Fig. 11, and Fig. 13 is a top plan view showing the coupler-head broken away to expose the lock and lock-tripping device.

My invention provides means by which in an extremely simple and efficient manner a coupler can be operated without the necessity of the workman passing between the cars and is enabled to perform the functions of locking, unlocking, lock-setting, and knuckle-throwing with a minimum of parts and with the least liability of getting out of order. It 40 45 is well known that these considerations are of great importance in the construction of car-couplers, and I believe that my invention more nearly approximates perfect conditions than has been attained heretofore.

50 My invention also provides an efficient side-opening coupler and enables the coupler-

head to be constructed with a closed top, which will exclude dirt or foreign substances from entering the coupling from above.

In the drawings, Fig. 1, 2 2 are coupler-heads. The knuckle 3 of each coupler-head preferably has at the rear end a hook portion 3' and has at its rear side a projecting lock-set shoulder 4, which is adapted to receive and hold the lock when in lock-set position, 55 as explained below. The knuckle is new in itself, in that it is the first knuckle which has a projecting lock-setting shoulder on its rear side alone or in combination with a hooked portion at the rear end. The knuckle is pivoted on a pin 5 and swings from the closed position (shown in Fig. 1) to the open position. (Shown in Fig. 3.)

The locking and opening piece 6 is made, preferably, in the form of an integral angled 70 piece, as shown in Fig. 7, and is best formed on its upper member *g* with a longitudinal groove 6', adapted to engage loosely with a rib 7 on the roof of the coupler-head. The piece 6 has a locking-head *b* and an opening-shank member *c*, at the lower end of which is a foot *d*, with which the opening-lever engages, by which said piece is raised and pushed forward. Above this foot on the locking and opening piece is a shoulder *e*, 75 adapted in lock-set position to engage with the shoulder 4 on the knuckle, as illustrated in Fig. 6. The lock has also an outwardly-projecting and upwardly-directed shoulder *f*, which when the coupler is locked, as shown 80 85 in Fig. 2, is vertically beneath the tail of the knuckle and prevents the lock from creeping upwardly when it is jarred by the surging movements of the car. In its forward motion the locking and opening piece is guided by a projecting wall or rib 8 in the coupler-head, Figs. 5, 6, and 9.

When the coupler is locked, the locking and opening piece is in its lowest position, Fig. 3, the opening member *c* being on the 95 rear side of the tail of the knuckle and the locking-head *b* on the front side thereof, with the upper horizontal member *g* fitting above or resting on the knuckle. The head *b* is confined between the knuckle-tail and the wall of the coupler-head, as shown in Figs. 1 and 3, and securely locks the knuckle, and

the locking and opening piece 6 is prevented from rising by the position of the shoulder *f*, directly beneath the tail of the knuckle, as shown in Figs. 2 and 3.

5 The unlocking and upward movement of the piece 6 is accomplished by a lever 9, fixed on a short cross-shaft 10, which is journaled in opposite walls of a vertical recess 11 in the floor of the coupler-head. When this shaft 10 has been inserted in position, it is prevented from being withdrawn accidentally by means of a recess 12 on the shaft, which engages a locking projection 13 on the coupler-head, so that the shaft can only be retracted in one 15 single position of its rotation. When the parts of the coupler have been assembled, the lever 9 prevents the shaft from getting into said position. The outer projecting end of the shaft preferably has a crank 14, 20 enabling it to be rotated by a suitable operating-rod. The lever 9 has a head 9', which is adapted to engage the shoe *d* at the foot of the opening member of the locking and opening piece. If when the parts are in the 25 locked position shown in Figs. 2 and 3 the operator desires to unlock the coupler, he turns the crank-shaft 10 by means of the operating-rod, thus raising the lever 9 into 30 engagement with the shoe *d* of the locking and opening piece. The locking and opening piece first moves forwardly and disengages the shoulder *f* from the under side of the knuckle-tail, and then it is lifted by the lever 9 along the guiding-surface 8, as illustrated in Fig. 5, until the locking-head *b* 35 passes above the level of the knuckle, and is thus freed from locking engagement therewith. If it is desired to leave the parts in lock-set position, the operator releases the 40 operating-shaft 10, whereupon the locking and opening piece drops slightly, and the lip *e* thereon will engage the shoulder 4 on the rear side of the knuckle-tail within the hooked portion thereof, thus supporting the 45 locking and opening piece in lock-set position, with its head still above the plane of motion of the knuckle-tail, Fig. 6. By reason of the construction of these parts the lock-setting will be effected even though the 50 knuckle may have been moved slightly forward, as the tendency of the lever 9 is to move the locking and opening piece into contact with the rear side of the knuckle. By forming the shoulder 4 on the rear side instead of on the top of the knuckle and locating it within the hooked portion of the knuckle the lock-setting can be accomplished by a shorter motion of the lever, and the coupler-head can therefore be made of 55 less height. This construction affords the further advantage that the lock will remain in lock-set position during a large arc of motion of the knuckle. If now the car to which the knuckle is applied be separated

from the companion car with which it is 65 coupled, the knuckle will swing freely open without any further manipulation on the part of the brakeman, and as it moves open it will eventually disengage the shoulder 4 from the lip *e*, and the locking and opening piece 6 will drop down until the locking-head of the lock rests upon the tail of the knuckle, in which position it will remain until the knuckle is again moved back into closed position, when the lock will fall into locking position. When it drops to locking position, the upper member *g* of the piece 6 will engage an inclined guiding surface *h* on the knuckle and will be directed thereby backwardly, so as to bring the shoulder *f* into its 80 confined position beneath the knuckle. If it is desired to trip the lock-set without first separating the car to which the knuckle is applied from the adjacent car, this can be done by means of a pin 15, which is inserted 85 through a hole in the wall of the coupler, as shown in Figs. 1 and 2, the position of the hole being such that the pin will engage the locking and opening piece, will lift it slightly so as to free it from the lip or shoulder 4, and cause it to drop back into its locking position. If it is desired to move the locking and opening piece beyond the lock-set position into the open position, and thus to positively move the knuckle open, the motion of 90 the lever 9 is continued beyond that which is shown by dotted lines in Fig. 6, and thereupon engaging the shoe *d* it will push the opening member of the piece 6 forwardly and will push the knuckle fully open. During this motion the groove 6' at the top of the locking and opening piece by engagement with the rib 7 at the roof of the coupler-head will prevent said piece from becoming displaced out of proper position. This is the 95 only function of the rib 7, since the work of opening is done by the pushing engagement of the lever 9 with the lower end of the opening member of the locking and opening piece, and, broadly speaking, my invention is not 100 limited to the employment of any such rib.

The opening of the knuckle is effected by the leverage of the lever 9, which is of considerable length, and therefore the efficiency of the device is not impaired by the fact that 115 the locking and opening piece engages the knuckle near its pivot-pin. The advantage of thus engaging the knuckle near its pivot is that a very wide opening of the knuckle can be obtained with a relatively short swing of the locking and opening piece. This adds 120 greatly to the practical usefulness of the device. As the lever is not attached to the lock, but is independent thereof, the parts will not bind and are not apt to be put out of order. When the knuckle has been thrown to its fully-open position, the operator releases 125 the opening mechanism, whereupon the lever

9 will drop back to its original position, (shown in Figs. 1, 2, 3,) the locking and opening piece 6 will drop, and its locking-head will rest upon the knuckle and will remain 5 there until the knuckle is again closed, when it will fall into locked position, as above explained.

In the drawings, on Sheet 4 thereof, I show a lock-tripping device of modified construction, which I may use in place of the pin 15 of Fig. 2. This device consists of a lever 16, journaled in a recess in the coupler-head and provided with a finger 17 and an upwardly-projecting horn 18. When the lock is moved 15 into lock-set position, the horn 18 is engaged by the lock and moves the finger 17 underneath the head g' of the lock. So long as the lock is in lock-set position the tripping device is in position to lift the lock up from the 20 shoulder 4, by reason of the engagement of the finger 17 beneath the lock. To trip the lock, the operator depresses the outer end of the lever 16, which projects outside the coupler-head.

25 The device described above may be modified in various ways by those skilled in the art without departure from my invention, as defined in the claims, since

What I claim is—

30 1. A coupler having an integral locking and opening member adapted to move forwardly and to engage the knuckle, and means for engaging the opening member to raise and push it forward to open the knuckle; 35 substantially as described.

2. A coupler having a locking and opening member adapted to swing forwardly at its lower portion to engage the knuckle, and a lever adapted to engage the lower portion of 40 said member and to raise it and push it forwardly; substantially as described.

3. A coupler having an integral locking and opening member adapted to engage the knuckle, and a lever adapted to engage the lower portion of said member and to push it forwardly, said lever being set in a vertical recess in the floor of the coupler-head; substantially as described.

4. A coupler having an integral locking 45 and opening member adapted to engage the knuckle, and means placed in a recess in the floor of the coupler-head adapted to engage said member and push it forwardly; substantially as described.

5. A coupler having an integral locking and opening piece comprising a locking head or member, and a rear opening member, and means for engaging the rear opening member and moving it forwardly to open the knuckle.

6. A coupler having a locking and opening piece, said piece having a locking member adapted to lock the front of the knuckle, an integral opening member at the rear of the knuckle, and an opening-lever adapted to

engage the lower portion of the opening 65 member and to push it against the knuckle; substantially as described.

7. A coupler having an integral angled locking and opening piece having a locking member and an opening member engaging 70 respectively opposite sides of the knuckle, and a lever adapted to engage the opening member from below to raise said piece and push the opening member forwardly; substantially as described.

75 8. A coupler having an integral angled locking and opening piece, having a locking member and an opening member engaging respectively opposite sides of the knuckle, and a lever adapted to engage the lower end 80 of said piece and to raise and push it forwardly; substantially as described.

9. A coupler having an angled locking and opening piece, a lever adapted to engage the lower end of the opening member and to raise 85 and move it forwardly, and a rib for confining and preventing displacement of the locking and opening piece; substantially as described.

10. A coupler having a vertical recess in the 90 floor, an opening-lever therein, and an integral locking and opening piece which rests in said recess when in locked position and is raised and moved forwardly by the lever; substantially as described.

95 11. A coupler having an upwardly-movable locking and opening piece, guiding portions in the coupler-head and means at its lower portion for engaging the opening member and raising it and moving it forwardly; 100 substantially as described.

12. A coupler having a knuckle and a lock provided with a shoulder adapted to engage the under side of the knuckle-tail when in locked position and to prevent the lock from 105 creeping; substantially as described.

13. A coupler having a knuckle and a lock provided with a shoulder adapted to engage the under side of the knuckle-tail when in locked position, and means for moving the 110 lock forward to disengage said shoulder and for raising it above the level of the knuckle; substantially as described.

14. A coupler having a knuckle and a locking and opening piece adapted successively 115 to assume the following positions: namely, a locking position wherein a shoulder on the locking and opening piece is in opposition to the knuckle and prevents it from creeping; second, a lock-setting position wherein it is 120 supported in unlocked position; and third, an opening position wherein it is moved forwardly to open the knuckle; substantially as described.

15. A coupler having a knuckle and a locking and opening piece adapted successively 125 to assume the following positions: namely, a locking position wherein a shoulder on the

locking and opening piece is in opposition to the knuckle and prevents it from creeping; second, a lock-setting position wherein it is supported on the knuckle in unlocked position; and third, an opening position wherein it is moved forwardly to open the knuckle; substantially as described.

16. A coupler having a locking and opening piece, means for swinging its lower end forwardly, means for engaging it with the knuckle in lock-set position, and means for tripping it, extending through the coupler-head; substantially as described.

17. A coupler having an upwardly-opening recess at its bottom extending below the pivotal knuckle, a knuckle-opening piece arranged to engage the knuckle and having a portion in said recess, and an operating-lever mounted in the recess and arranged to engage and move the opening-piece.

18. An angled coupler locking and opening piece having at its lower end a shoe for engagement with a lever; substantially as described.

19. An angled coupler-lock having a shoulder adapted to engage the knuckle to prevent upward creeping and a guiding-surface on the knuckle to direct the lock into position where the shoulder will be confined by the knuckle; substantially as described.

20. An angled coupler locking and opening piece having on its upper member a groove adapted to engage a projection on the coupler-head; said groove extending lengthwise of the upper member of the angled piece substantially as described.

21. An angled coupler locking and opening piece having at its lower end a shoe for engagement with a lever and a locking-head on said piece; substantially as described.

22. A coupler provided with a knuckle locking and opening piece having its upper end confined by the coupler-head and its lower end free to swing, and means for engaging the lower portion of the locking and opening piece to swing the same on its upper confined end as an axis.

23. A coupler having a knuckle locking and opening piece, there being a loose rib-and-groove engagement between the top of

said piece and the coupler-head upon which the piece is adapted to swing, said rib and groove extending lengthwise of the upper member of the locking and opening piece, and means for swinging said piece.

24. A coupler having a recess in the upper side of its bottom, below the pivotal knuckle, a locking and opening piece, a rotary shaft journaled in the coupler-head across the recess, and a lifting-lever operated by the shaft, working in the recess and engaging the locking and opening piece.

25. A coupler having a knuckle locking and opening piece, a lever for engaging and swinging its lower end forwardly, means for confining its upper portion, and guiding portions on the coupler-head, the lever being set in a vertical recess across which its shaft extends; substantially as described.

26. A coupler having a locking and opening piece adapted to rise and to swing forwardly at its lower end, said locking and opening piece and the rear side of the knuckle-tail being formed with projections adapted to engage in lock-setting, and the coupler being formed with means for confining the upper end of the locking and opening piece during its forward motion, and means applied to the lower portion of said piece for moving it; substantially as described.

27. A coupler having an opening member adapted to swing forwardly at its lower portion to engage the knuckle at a point near its pivot, and a lever which engages the lower portion of said member and pushes it against the knuckle; substantially as described.

28. A coupler having a knuckle, and an upwardly-movable lock, having a projection adapted when the lock is locked to engage the knuckle and to prevent the lock from creeping, and means for imparting lateral motion to the lock to remove the projection from beneath the knuckle when the lock is lifted; substantially as described.

In testimony whereof I have hereunto set my hand.

ARTHUR JAMES BAZELEY.
